UNITED STATES PATENT OFFICE.

JOHN J. SULLIVAN, OF IPSWICH, MASSACHUSETTS.

MACHINE FOR SEWING ON BUTTONS.

SPECIFICATION forming part of Letters Patent No. 596,020, dated December 21, 1897.

Application filed January 14, 1896. Renewed November 12, 1897. Serial No. 658,340. (No model.)

To all whom it may concern:

Be it known that I, JOHN J. SULLIVAN, a citizen of the United States, residing at Ipswich, in the county of Essex and State of Massachusetts, have invented certain new and useful Improvements in Button-Sewing Machines, of which the following is a specification, reference being had therein to the accompanying drawings.

This invention relates to a machine similar in many respects to the machine embraced by my application, Serial No. 541,860, filed March 15, 1895, and in which machine the needle is periodically given a series or succession of horizontal movements, while the work remains stationary, for the purpose of attaching each button to the work by a series of overseaming stitches formed by passing the needle through the eye of the button-shank and the work and through the work outside of the said eye alternately. In other words, the series of button-attaching stitches for each button is formed by mechanism which changes the relative horizontal positions of the needle and the work at each stitch for a series of stitches, so that the needle will pass through and outside of the eye of the button-shank alternately. In the present machine, as in the machine embraced by my said application, the horizontal or overseaming movements of the needle are periodically suspended and an automatic work-feed (which is idle or inoperative while the button-attaching stitches are being formed) operates to advance the work to the next button-sewing position; but this work-feed might, in either machine, be omitted and the work be fed by the operator. In the present machine the button-feeder, which transfers the buttons from the lower end of the button-chute to sewing position, is operated automatically, thus making the button-supplying and button-feeding mechanism entirely automatic.

In the accompanying drawings, Figure 1 is a rear side elevation of my improved machine. Fig. 2 is a plan view of the same. Fig. 3 is a detail view showing part of the work-supporting arm, the lower part of the button-chute, and adjacent parts. Fig. 4 is a detail plan view of the cam-cylinder and feed-regulating devices. Fig. 5 is a detail view of the button-feeder and its shaft, and Fig. 6 a detail view

of the presser-foot. Figs. 7, 8, and 9 are detail views to show the button-guard.

A denotes the standard of the machine-frame and from which standard extend forward horizontally the integral overhanging arm A' and the work-supporting arm or cylinder A², these three parts constituting the frame of the machine. B is the driving-shaft, 55 journaled in the frame and carrying at its forward end a cylinder b, having a cam-groove for operating the take-up lever b' and a crank-pin connected by a link or pitman b² with the needle-bar f. The stitch-forming and work-feeding mechanism of the machine herein shown is that of the well-known Singer oscillating-shuttle machine, the rocking-shuttle-operating shaft C being actuated from the crank c of the driving-shaft through the pitman c' and rocker c², as is common with machines of this class.

D is the feed-operating rock-shaft, having at its rear end an arm d, to which is jointed the lower end of the connecting-rod d', forked at its upper end to embrace the feed-cam d² on the shaft B. The rock-shaft D imparts the horizontal or feeding movements to the feed-dog at the forward end of said shaft, and the extent of such feeding movements or 75 the entire suspension thereof depends on the relative positions of adjustment of the rod d', the link d³, and the arm d⁴ of the feed-controller, said link being jointed at its upper end to said rod d' and at its lower end to said arm, this being the well-known Singer toggle-feed. The arm d⁴ is fast to the rear end of a short feed-controlling shaft d⁵, having at its forward end a second rigid arm d⁶, provided with an adjustable pin or roller-stud 80 d⁷, extending into a slot in a lever d⁸, pivoted at d⁹ to the machine-frame and having in turn at its free end a pin or roller-stud d¹⁰, extending into a cam-groove in the rear face of the cam-cylinder E, loosely mounted on the 85 driving-shaft B and intermittently rotated by a cam-actuated lever-dog e, engaging teeth e', formed on said cam-cylinder and operating as fully described in United States Patent No. 541,840, dated July 2, 1895. The 90 cam-groove in the cylinder E, into which the roller-stud carried by the lever d⁸ extends, serves at the proper times to move the feed-controlling shaft d⁵, so that the arm d⁴ thereof

will be in such positions as to cause the feed to operate or to be entirely suspended, as in the machine described in my application hereinbefore mentioned.

5 The needle-bar f is reciprocated vertically in a horizontally-movable frame F , pivoted on center screws f' and having a short horizontal arm f^2 , connected by the rod or link f^3 with the free end of a horizontal lever f^4 , 10 pivoted at f^5 and provided between its ends with a pin or roller-stud entering a cam-groove e^2 in the cam-cylinder E , said cam-groove having a serpentine or acting portion 15 part way around the said cylinder and a straight or non-acting portion the rest of the distance around said cylinder, so that the needle-bar and needle will be moved horizontally to make a series of overseaming-strokes while the feed of the work is suspended and 20 will then have its horizontal movements suspended to form a series of plain or successively-disposed stitches when the feed is operating, as in the machine described in my former application referred to, the cams controlling the feed and the horizontal movements of the needle-bar being relatively so arranged as to secure these results.

To vary the lengths of the plain stitches formed between the overseaming or button-30 attaching stitches and thus vary the spacing of the buttons, the pin or stud d^7 is adjustable in the slotted arm d^6 of the shaft d^5 and in a slot in the lever d^9 by means of the feed-regulating screw d^{11} , so that the feed can be 35 varied in a well-known manner.

G is the button-hopper, from which the buttons pass down through the button-chute H to the needle, the lower end of said chute being adjacent to the work-plate or throat-plate 40 I , the button-shank slot h at the said lower end of said chute registering with a slot k in the presser-foot K . The driving-shaft B is provided with a worm b^3 , meshing with a worm-wheel g on the lower end of a vertical shaft 45 g' , extending up within the hopper G and carrying a series of brushes g^2 , which serve to force the buttons from said hopper into the chute H , said hopper having in its bottom a slot g^3 for receiving the shanks of the buttons 50 and which slot communicates with the upper end of the slot h of the button-chute, as in my prior machine. To insure a more perfect button-feeding operation of the brushes g^2 , I provide the bottom of the hopper with one or 55 more brush-lifters g^4 , which may be either plates or wires and which have inclined parts up which the brushes will ride. When in their operation the rotating brushes reach the rear ends of said lifters, they fall by their 60 own resilience onto the buttons the shanks of which are entered into the slot g^3 and thereby hold them in the said slot, so that they cannot fail to be forced out of the button-exit of the hopper into the chute H so long as there 65 is room for them in said chute, which will thus always be unfailingly supplied with buttons. A guard p in the hopper, overlapping

the upper end of the slot h , prevents the buttons the shanks of which are not entered in the slot g^3 from clogging the button-entrance 70 to said chute.

A small detaining-spring h' at the lower end of the button-chute prevents the buttons from escaping therefrom except as they are positively removed by the button-feeder, which 75 feeder is similar to that of my prior machine in that it consists of a horizontally-movable or swinging arm m , attached to the lower end of a vertical rock-shaft M , having at its upper end an arm m' , joined by a rod m^2 to the 80 lower or free end of a lever m^3 , pivoted at m^4 and having between its ends a pin or roller, stud m^5 , entering the cam-groove e^3 of the cylinder E . The spring m^6 between the collar m^7 on said rod and the lever m^3 forms a 85 yielding connection between said lever and rod, so that the feeder m can accommodate itself to different sizes of buttons or irregularities in the shapes of buttons of similar size, the said lever in the backward movement 90 of the button-feeder engaging the collar m^8 , secured to the rod m^2 .

For convenience in emptying the button-hopper, as when said hopper is to be supplied with buttons of a different size, I provide the 95 side of said hopper with an opening which extends to the bottom of the hopper, said opening being normally closed by a removable gate g^5 , which is held in place by the spring g^6 , but which can be removed by sliding the 100 same upward in the dovetailed recess provided for it in the side of the hopper.

The throat-plate I is provided, beneath the presser-foot K , with a raised portion i , so that the shanks of the buttons can be held level 105 during the attaching operation, and in order to do this with large-sized buttons said throat-plate is also preferably formed with a groove or slot i' to receive the heads of these large buttons without requiring the raised part i to 110 be so high as to be too much elevated above the shuttle or other loop-seizing device constituting a part of the stitch-forming mechanism.

The groove i' , it will be observed, has a level 115 bottom or, in other words, is something more than a mere pocket to receive the head of the button, this level bottom of the groove permitting the button, after it has been attached to the work, to be fed forward with the latter 120 without requiring the head of the button to be raised from the groove or slot.

My machine is preferably provided with an automatic stop-motion mechanism, which I 125 will now describe.

The driving-shaft B is provided at its rear end with the loose pulley b^4 and fast pulley b^5 .

N is a starting and stopping lever having a belt-shifter n for transferring the driving-belt from the loose pulley to the fast pulley, 130 or vice versa, and having also an arm n' to be engaged by a hook on the rear end of a retaining-latch n^2 , the upper end of said lever being pressed outward or toward said pulleys

by the spring n^3 , interposed between the standard A and said lever. Rigid with the lever N is an arm N', to be connected by a rod n^4 with a treadle which, when pressed upon by the operator, will remove the belt from the loose to the fast pulley, or will hold the said lever N in position to keep the machine in operation. The inner or forward end of the latch n^2 extends within range of a pin e^5 on the cam-cylinder E, so that at the proper time in the rotation of said cylinder, when a series of button-attaching stitches have been completed, said pin will trip said latch and release its rear end from engagement with the arm n' of the lever N to permit the machine to be stopped. This tripping mechanism would normally cause the machine to be automatically stopped at each rotation of the cam-cylinder E after each button had been attached; but so long as the operator presses down on the treadle the said tripping mechanism will be inoperative and the machine will continue to run to sew on a series of buttons, but when the last button of a series or of a shoe is being sewed on the operator will remove his foot from the treadle, so that the machine will be automatically stopped at the proper time. The lever N is provided with a yoke comprising the brake-arms n^5 and n^6 , the former to be acted on by a tappet b^5 on the fast pulley b^5 to press the arm n^6 against said fast pulley. A spring-acted latch n^7 on the arm n^5 is intended to catch over the tappet b^5 to prevent back motion when the machine is suddenly stopped. This stop-motion mechanism just described is not new with me, however, and is merely illustrated as showing a convenient form of such mechanism which may be employed.

40 The presser-foot may be raised to release the work by the ordinary lifter h' or by a lever O to be connected with a knee-lever or treadle.

The general operation of this machine is essentially the same as the machine embraced by my prior application referred to, excepting that in the present machine the button-feeding mechanism is entirely automatic. The machine being started, the buttons are transferred at the proper time from the lower end of the button-chute to sewing position by the button-feeder m. Each button is attached to the work by a series of overseaming-stitches (in the present instance twelve) passing alternately through the eye of the button-shank and the material and through the material outside of said eye, these overseaming or button-securing stitches in one place or piled on top of each other being due to the horizontal movements of the needle-bar and needle while the operation of the feeding mechanism is suspended. The series of stitches to sew on a button having been completed, the horizontal movements of the needle-bar and needle are suspended and the feed is thrown into operation to advance the work to position for the next button,

thereby forming a series of plain stitches between the button-securing stitches, and these operations are repeated until all the buttons 70 of a button piece or shoe have been sewed on, when the machine will be automatically stopped, as above described.

In the machine herein shown the horizontal movements of the needle-bar and needle 75 to form the button-attaching stitches are in a direction transverse to the work-supporting arm or cylinder A² or in the direction of the feed of the work, but this is not essential; nor is it essential to the gist of my present 80 invention that the overseaming or button-attaching stitches should be formed by moving the needle-bar and needle horizontally, as it is obvious that they may be formed by reciprocating the work beneath a needle having no horizontal movements by a properly-constructed feeding mechanism, these two ways of forming overseaming-stitches being well-known equivalents of each other in the art of mechanical sewing. I therefore wish 85 it understood that my invention comprises the combination, with an automatic button-feeding mechanism, of a mechanism for forming a series of three or more button-attaching stitches for each button, either with or 90 without an automatic feeding mechanism for advancing the work to space the buttons, as also either with or without an automatic stop-motion mechanism which will suspend the 95 operation of the machine when desired. 100

Having thus described my invention, I claim and desire to secure by Letters Patent—

1. In a button-sewing machine, the combination with a stitch-forming mechanism comprising automatic means for changing the relative horizontal positions of the needle and the work for a series of three or more times in succession, to form a series of button-attaching stitches in one place and which pass 105 alternately through the eye of a button-shank and the work and through the work outside of the said eye, of automatic means for periodically suspending the operation of the device which changes the relative horizontal 110 positions of the needle and work during the time required for making a series of successively-disposed stitches, without stopping the machine, and an automatic button-feeding mechanism for successively presenting the 115 buttons to the said stitch-forming mechanism. 120

2. In a button-sewing machine, the combination with a stitch-forming mechanism comprising means for reciprocating the needle-bar and needle horizontally a series of three 125 or more times in succession while the work remains stationary, to form a series of button-attaching stitches in one place and which stitches pass alternately through and outside of the eye of a button-shank, of automatic 130 means for suspending the horizontal movements of the needle during the time required to make a series of successively-disposed stitches, without stopping the machine, when

a predetermined number of button-attaching 6c
stitches have been made, and an automatic
button-feeding mechanism for successively
presenting the buttons to said stitch-forming
mechanism.

3. In a button-sewing machine, the combination
with a stitch-forming mechanism comprising
automatic means for changing the relative
horizontal positions of the needle and the
work for a series of three or more times in
succession, to form a series of button-attaching
stitches in one place and which pass through
the eye of the button-shank and the work and
through the work outside of the said eye, of
automatic means for periodically suspending
the operation of the mechanism which changes
the relative horizontal positions of the needle
and work, an automatic button-feeding
mechanism for successively presenting the
buttons to the said stitch-forming mechanism,
and a mechanism for automatically stopping
the machine when a desired number of stitches
has been formed.

4. In a button-sewing machine, the combination
with a stitch-forming mechanism comprising
means for reciprocating the needle-bar and
needle horizontally a series of three or more
times in succession while the work remains
stationary, to form a series of button-attaching
stitches in one place and which pass alternately
through and outside of the eye of a button-shank, of
automatic means for suspending the horizontal movements
of the needle, during the time required to make
a series of successively-disposed stitches, and
without stopping the machine, when a predetermined
number of button-attaching stitches have thus
been formed, an automatic button-feeding
mechanism for successively presenting the
buttons to said stitch-forming mechanism,
and an automatic work-feeding mechanism
for advancing the work to space the
buttons.

5. In a button-sewing machine, the combination
with automatic button-feeding devices, of a
stitch-forming mechanism comprising a horizontally-movable
needle-bar and needle, and an automatic work-feeding
mechanism, independent of said needle-bar and
needle, for advancing the work to space the
buttons, of an automatic mechanism acting
to suspend the work-advancing action of the
feed and the horizontal movements of the
needle, alternately, and without stopping the
machine and during the time required for
making a series of button-attaching stitches
and a series of plain or successively-disposed
stitches, respectively, whereby overseaming
or button-attaching stitches will be formed

when the work is at rest and plain or successively-disposed 6c
stitches will be formed between the buttons.

6. In a button-sewing machine, the combination
with a stitch-forming mechanism comprising a needle and means for imparting vertical and horizontal movements thereto, of an independent automatic work-feeding mechanism, automatic devices for presenting buttons to the said needle, a needle-bar-controlling cam by which lateral movements are imparted to the needle periodically and which also serves to suspend the said horizontal movements during the time required to make a series of successively-disposed stitches, and a feed-controlling cam to throw the feed into 75 and out of operation, said cams being so timed relative to each other that when the horizontal movements of the needle are suspended the work-feeding mechanism is operative, and when the said work-feeding mechanism is inoperative, horizontal movements 80 will be imparted to the said needle.

7. In a button-sewing machine, a throat-plate provided with a raised portion, to sustain the shank of a button in a level position, 85 and with a level groove or slot adjacent to said raised portion, in combination with stitch-forming, work-feeding and button-feeding mechanism.

8. In a button-sewing machine, the combination with stitch-forming appliances, of a button-hopper having interiorly at its bottom rotating brushes, one or more lifters, at the bottom of said hopper, for raising said brushes so that they may be caused to bear on the 95 buttons to be fed from said hopper, and means for conducting the buttons to said stitch-forming appliances.

9. The combination with the button-hopper G, having the slot g^3 in its bottom of proper 100 size to admit the shanks of the buttons while excluding their heads, of the button-chute H having the button-shank slot h connecting with the said button-shank slot g^3 , and the guard p extending into the bottom of said 105 hopper and arranged to overlap the upper end of the said slot h of the button-chute, said guard serving to prevent the buttons whose shanks are not entered in said slot g^3 from clogging the button-entrance to the said 110 chute.

In testimony whereof I affix my signature
in presence of two witnesses.

JOHN J. SULLIVAN.
